(57) **CLAIM**

The ornamental design for a false ceiling as shown and described.

DESCRIPTION

The patent or application file contains at least one drawing executed in color. Copies of this patent of patent application with color drawing(s) will be provided by the Office upon request and payment of the necessary fee.

FIG. 1.1 is a front elevational view for a false ceiling showing our new design;

FIG. 1.2 is a rear elevational view thereof;

FIG. 1.3 is a left-side elevational view thereof;

FIG. 1.4 is a right-side elevational view thereof;

FIG. 1.5 is a top plan view thereof;

FIG. 1.6 is a bottom plan view thereof;

FIG. 1.7 is a front, left-side, and top perspective view thereof;

FIG. 1.8 is a front, left-side, and bottom perspective view thereof;

FIG. 1.9 is a front and bottom perspective view thereof;

FIG. 1.10 is a bottom plan view thereof with the false ceiling shown in a condition of use, with the suspended spherical elements in alternate positions,

FIG. 1.11 is a bottom plan view thereof with the false ceiling shown in another condition of use, with the suspended spherical elements in alternate positions,

FIG. 1.12 is a bottom plan view thereof with the false ceiling shown in another condition of use, with the suspended spherical elements in alternate positions.

FIG. 1.13 is a partial enlarged view of the indicated area "1.13" in FIG. 1.1;

FIG. 1.14 is a partial enlarged view of the indicated area "1.14" in FIG. 1.1;

FIG. 1.15 is a partial enlarged view of the indicated area "1.15" in FIG. 1.1;

FIG. 1.16 is a partial enlarged view of the indicated area "1.16" in FIG. 1.1;

FIG. 1.17 is a partial enlarged view of the indicated area "1.17" in FIG. 1.1;

FIG. 1.18 is a partial enlarged view of the indicated area "1.18" in FIG. 1.1;

FIG. 1.19 is a partial enlarged view of the indicated area "1.19" in FIG. 1.1;

FIG. 1.20 is a partial enlarged view of the indicated area "1.20" in FIG. 1.5;

FIG. 1.21 is a partial enlarged view of the indicated area "1.21" in FIG. 1.5;

FIG. 1.22 is a partial enlarged view of the indicated area "1.22" in FIG. 1.7;

(Continued)

FIG. 1.23 is a partial enlarged view of the indicated area "1.23" in FIG. 1.7;
 FIG. 1.24 is a partial enlarged view of the indicated area "1.24" in FIG. 1.7;
 FIG. 1.25 is a partial enlarged view of the indicated area "1.25" in FIG. 1.7;
 FIG. 1.26 is a partial enlarged view of the indicated area "1.26" in FIG. 1.7;
 FIG. 1.27 is a partial enlarged view of the indicated area "1.27" in FIG. 1.7; and
 FIG. 1.28 is a partial enlarged view of the indicated area "1.28" in FIG. 1.7.

The broken lines seen in Figures 1.1, 1.5, 1.7, and 1.13 through 1.28 depict the boundaries of the enlargements and form no part of the claimed design.
